Primary Examiner — Elizabeth J Oswecki(74) *Attorney, Agent, or Firm* — Perkins Coie LLP(57) **CLAIM**

The ornamental design for a cover lens frame, as shown and described.

DESCRIPTION

FIG. 1 is a perspective view of a cover lens frame showing our new design;

FIG. 2 is a top view thereof;

FIG. 3 is a front view thereof;

FIG. 4 is a back view thereof;

FIG. 5 is a bottom view thereof;

FIG. 6 is a right side view thereof; and,

FIG. 7 is a left side view thereof.

The broken lines illustrate environmental features that form no part of the claimed design.
